UNITED STATES PATENT OFFICE.

WILLIAM W. COREY, OF ST. LOUIS, MISSOURI, ASSIGNOR TO PRATT & CADY COMPANY, OF HARTFORD, CONNECTICUT, A CORPORATION OF CONNECTICUT.

HYDRANT.

SPECIFICATION forming part of Letters Patent No. 750,021, dated January 19, 1904.

Application filed November 28, 1903. Serial No. 183,033. (No model.)

To all whom it may concern:

Be it known that I, WILLIAM W. COREY, a citizen of the United States, residing at St. Louis, in the State of Missouri, have invented 5 certain new and useful Improvements in Hydrants, of which the following is a specification.

This invention relates to a hydrant which has a drip-outlet through the bottom, which is closed when the main valve is opened and is 10 opened when the main valve is closed for the escape of water remaining in the case and stand-pipe after the main valve has been closed.

The object of this invention is to provide a very simple and cheap construction whereby 15 the main valve is easily opened and closed by a powerful mechanism and the drip-valve, which is simple in construction and durable in use, is positively opened and closed by a simple and cheap mechanism.

20 The embodiment of the invention that is illustrated has a case which is adapted to be connected with a water-main and with a stand-pipe and has a port which is adapted to be opened and closed by a swinging valve that is 25 oscillated by the movement of a nut up and down a thread on the spindle, which is supported by a block that is loosely held in the case and that guides the drip-valve stem, which is also moved up and down by a nut that fits 30 a thread on the spindle, so that when the main valve is closed the drip-valve is opened and when the main valve is opened the drip-valve is quickly closed, the spindle, main valve, block, and drip-valve being removable 35 together from the case, if it is desired to renew or repair the seats or faces of either of the valves.

Figure 1 of the accompanying drawings shows a central section of the case of a hydrant that embodies this invention with the main valve opened and the drip-valve closed. Fig. 2 shows a section of the lower end of the case with the drip-valve opened. Fig. 3 shows a section of the case on the plane indicated by 45 the dotted line 3-3 on Fig. 1. Fig. 4 shows a plan of the block. Fig. 5 shows a rear elevation of the block.

The case 1 is preferably cast to shape of iron with an end 2, adapted to be attached to a water-main and an end 3, adapted to be fastened to the stand-pipe. The valve-seat 4 around the inlet-port is inclined, so that water which flows through from the main is directed upwardly toward the stand-pipe. The main valve 5 has an arm 6, that is hinged to a block 7, so that the valve may be swung against the inclined seat to close the port or drawn back from the inclined seat so it will not interfere with the flow of water from the port to the stand-pipe.

50 The block 7 has wings 8, that are adapted to rest upon lugs 9, that extend from the back wall near the bottom of the case. The block also has a forwardly-extending tubular part 10, that fits into the upper end of the lining 11 55 of the drip-outlet 12. The back of the block bears against the back wall of the case as the wings rest upon the lugs, and the forwardly-extending tubular portion projects into the drip-opening and prevents the block from 60 turning sidewise out of place. Openings 13 are made through the side wall of the tubular projecting portion of the block for the outflow of drip-water.

65 The lower end of the spindle 14 rests in a socket in the upper end of the block. This spindle has a coarse thread 15, upon which moves a nut 16, that is connected by a link 17 with the back of the main valve. When the spindle is turned in one direction, this nut is 70 lowered and the main valve is moved to its seat. When the spindle is turned in the opposite direction, the nut is raised and the main valve is drawn back from its seat against the spindle. All downward thrust upon the block incident 75 to the closing of the main valve is sustained by the lugs that project from the back wall near the bottom of the case. The backward thrust is sustained by the back wall of the case, and all sidewise twisting is resisted by the engagement of the back of the block with the wall of the case and the engagement of the forwardly-extending tubular part of the block with the walls of the lining through the drip-opening.

The spindle also has a fine thread 18, on which moves a nut 19, that is fastened to the drip-valve stem 20. This stem extends down through an opening in a lug 21, that projects 5 outwardly from the upper end of the block and through an opening in the tubular forward extension of the block. Secured to the lower end of this stem is an upwardly-opening cup-packing 22. This packing is shaped 10 to tightly fit the reduced section of the lining to the drip-opening. When the spindle is turned to open the main valve, the drip-valve packing is drawn upwardly from the enlarged section of the lining of the drip-opening into 15 the reduced section, so as to tightly close the drip-opening. The tightness of this packing is augmented by the action of the water-pressure against the sides of the packing. When the spindle is turned for closing the main valve, 20 the drip-valve is moved downwardly, and just as the main valve is closed the drip-valve packing passes from the reduced section to the enlarged section of the lining to the drip-opening. The main valve, the drip-valve, and 25 the supporting-block are all removed together when the spindle is lifted out of the case and of course all are set together. No special fitting is required for these parts, which are simple to construct, and all the parts are 30 positively held against such yielding as would cause binding when the main valve is opened and closed. A drip-valve of approved form is connected in a simple and cheap manner with the spindle, so that both valves must 35 operate together in a positive manner, and the block which supports the spindle and the main valve and guides the drip-valve is firmly held in position in a simple manner.

The invention claimed is—

- 40 1. A hydrant having a main valve adapted to open and close a port part way up the case, a drip-valve adapted to open and close an opening through the bottom of the case, a block loosely held near the bottom of the case, a spindle with two threads supported by the block, a nut movable on the upper thread and connected with the main valve, and a nut mov-

able on the lower thread and connected with the drip-valve, substantially as specified.

2. A hydrant having an inlet-port part way 50 up the case, a drip-opening at the bottom of the case, a block loosely supported near the bottom of the case and having a portion that extends into the drip-opening, a spindle with two threads loosely supported by the block, 55 a main valve hinged to the block, a nut movable on the upper thread of the spindle, a link connecting the nut on the upper thread with the main valve, a drip-valve movable in the drip-opening and having a stem extending 60 through a portion of the block, and a nut movable on the lower thread of the spindle and connected with the drip-valve stem, substantially as specified.

3. A hydrant having an inlet-port part way 65 up the case, a drip-opening through the bottom of the case, a block loosely supported near the bottom of the case and having a forwardly-extending portion that enters the drip-opening, a spindle with two threads supported by the 70 block, a valve hinged to the block, a nut movable on the upper thread of the spindle, a link connecting the nut on the upper thread with the back of the main valve, a drip-valve movable in the drip-opening, a nut movable on the 75 lower thread of the spindle, and a valve-stem connecting the nut movable on the lower thread with the drip-valve and extending through the forwardly-extending portion of the block, substantially as specified. 80

4. A hydrant having a main valve adapted to open and close a port, a drip-valve adapted to open and close an opening, a block held near the bottom of the case, a spindle with two threads supported by the block, a nut movable on one thread and connected with the main valve, and a nut movable on the other thread and connected with the drip-valve, substantially as specified. 85
